STOVE OR THE LIKE

Verne F. Dale, Onalaska, Wis., and Herman Dorfman, Chicago, Ill.; said Dale assignor to said Dorfman

Application January 5, 1949, Serial No. 66

Term of patent 3½ years

(Cl. D81—10)

To all whom it may concern:

Be it known that we, Verne F. Dale and Herman Dorfman, respectively a citizen of the United States of America residing at Onalaska, Wisconsin, and a citizen of the United States of America, residing at 2600 North Kimball Avenue, Chicago, Illinois, have invented a new, original, and ornamental Design for a Stove or the like, of which the following is a specification, reference being had to the accompanying drawing, forming part thereof.

In the drawing:

Figure 2 is another perspective view of the same, said doors being shown in the closed position;

We claim:

The ornamental design for a stove or the like, as shown.

VERNE F. DALE.
HERMAN DORFMAN.
